REEL

John E. Ball, Detroit, Mich.

Application March 15, 1932. Serial No. 598,964

3 Claims. (Cl. 242—110)

This invention relates to reels and more particularly to dispensing reels for wire, cable or similar materials.

The principal object of the invention is to provide a reel of novel construction which will facilitate the handling and dispensing of materials employed in building construction.

Another object of the invention is to provide a reel which may be compactly folded when not in use.

A further object of the invention is to provide a reel which will accommodate coils of different diameters.

A still further object of the invention is to provide dispensing reels which are adapted to be suspended from convenient supports and which will in turn support other dispensing reels.

Other features and advantages will become apparent from the following description and appended claims.

In carrying out my invention, I have devised a dispensing reel which is particularly adapted for handling coils of wire or cable or similar materials used in connection with building construction or reconstruction.

For a better understanding of the invention reference may be had to the accompanying drawing forming a part of application, wherein:

Figure 1 is a perspective view of a dispensing reel constructed in accordance with this invention and having supported thereon a section of a coil of wire,

Fig. 2 is a similar view illustrating the arrangement of a plurality of reels and the means for suspending said reels one from the other,

Fig. 3 is a side elevation of the above mentioned reel shown in folded position, and

Fig. 4 is an end view of the device shown in Fig. 3.

Referring to the drawing, wherein like numerals designate similar parts throughout, I have indicated the preferred construction of my invention as embodied in a reel comprising a pair of sheet metal straps bent to form substantially triangularly shaped loop members 11 and 12, which are of substantially identical contour except that one is slightly smaller than the other, so that they may be nested one within the other, as illustrated in Figs. 3 and 4. The members 11 and 12 are pivotally connected at the points 13 and 14 by eye bolts 15 and 16 respectively. The eye bolt 15 is left slightly open so that it may freely engage an overhead support or an eye bolt 16 of another reel. Nuts 17 are preferably threaded upon the shanks of eye bolts 15

and 16 and riveted thereto to prevent disengagement of the nuts from the eye bolts during the use of the reel. Side members 20 of the loop members 11 and 12 may be bent inwardly as indicated at 21 to provide downwardly diverging surfaces of different angles with respect to the vertical for the accommodation of differently sized coils of the material to be dispensed. The loop members are preferably closed at the bottom of the reels and extended overlapping portions 22 and 23 are provided to increase the rigidity and strength of the bottom portion of the reel so that other reels may be suspended therefrom. These overlapping portions may be interconnected by any suitable means such as rivets 24.

When not in use the members 11 and 12 may be rotated on eye bolts 15 and 16 and into telescoping relation so that the reel may be easily carried and take up the minimum space in an electrician's tool kit. Although the loop members 11 and 12 are preferably constructed of sheet metal straps, it is obvious that strap, tubular, bar, or other materials of any desired cross section may be employed in the construction of these members.

In using this device, the members 11 and 12 are rotated on the eye bolts 15 and 16 until they are disposed at approximately right angles to each other as indicated in Figs. 1 and 2. A coil 25 or 26 of a material to be dispensed is then placed upon the device and the reel is suspended by the upper eye bolt 15. The material of the coil maintains the members 11 and 12 in extended relation so that no other locking means is necessary. If it is desired to dispense material from several coils, other devices of the same kind may be suspended from the first reel by connecting the lower eye bolt 16 of one reel to the top eye bolt 15 of the next adjacent reel.

The eye bolts 15 and 16 freely swivel in the members 11 and 12 so that when employing a number of suspended reels, as indicated in Fig. 2, the individual reels may be rotated in either the same or opposite directions independently of one another to dispense the material from these reels. It is desirable to suspend the reels above the floor level since the floors are usually employed in the course of building construction for the disposal and transportation of other building materials. The reels may be employed to dispense wire, cord material, flexible conduit, cables, sheathing or other desired material employed in building construction.

I have thus provided for the dispensing of ma-

terial from reels suspended from the overhead which insures the paying off of the material without kinking or fouling and eliminates the danger of injury incident to dragging the material across 5 wet or obstructed floors or running over the material with the vehicles employed for the transportation of other building material.

As many changes could be made in the above described construction and many apparently 10 widely different embodiments of this invention could be made without departing from the scope thereof, it is intended that all matter contained in the above description or shown in the accompanying drawing, shall be interpreted as illustrative and not in the limiting sense.

I claim:

1. A reel comprising a plurality of loop members having downwardly diverging sides and means for pivotally connecting said members at 15 the tops and bottoms thereof.
2. A reel comprising substantially triangularly shaped loop members having overlapping portions

secured together at the bottom of said members, one member being slightly smaller than the other so as to be received in the latter, the sides of said members diverging downwardly, means projecting through the tops of both members for pivotally connecting the members and hook shaped suspension means secured to said pivot means.

3. A reel comprising substantially triangularly shaped loop members having overlapping portions secured together at the bottom of said members, one member being slightly smaller than the other so as to be received in the latter, the sides of said members diverging downwardly, means projecting through the tops of both members for pivotally connecting the members, hook shaped suspension means secured to said pivot means, means projecting through the bottom of both members for pivotally connecting the members and suspension means secured to the last-mentioned pivot means.
